HAL R. STAFFORD, OF PLAINFIELD, NEW JERSEY, ASSIGNEE OF ONE-THIRD TO JOHN E. MUHLEFELD, OF SCARSDALE, NEW YORK.

LOCOMOTIVE EXHAUST-PIPE.

1,306,444.

Specification of Letters Patent. Patented June 10, 1919.

Application filed November 11, 1918. Serial No. 262,001.

To all whom it may concern:

Be it known that I, HAL R. STAFFORD, of Plainfield, in the county of Union and State of New Jersey, have invented a certain new and useful Improvement in Locomotive Exhaust-Pipes, of which improvement the following is a specification.

My invention relates to locomotive exhaust pipes, of the "double nozzle" type, i. e., those in which the exhaust steam from two locomotive cylinders is discharged to the stack through separate orifices or nozzles. The object of my invention is to provide an exhaust pipe of such type in which the entraining surface, through which, in operation, the exhaust steam acts upon the gases of combustion, may be materially increased, and back pressure upon the pistons of the locomotive be minimized, it being well recognized that the efficiency of the exhaust blast in a locomotive smoke box is dependent, directly, upon the area of the entraining surface of the jet, and, inversely, on the back pressure induced on the pistons. Further objects of my invention are to provide an exhaust pipe which will present as slight resistance as possible to the flow of the smoke box gases, in approaching the entraining surfaces of the exhaust jet, and means for readily varying the area of the exhaust nozzle, as may, from time to time, be desired.

The improvement claimed is hereinafter fully set forth.

Various designs of exhaust nozzles have been proposed and experimented with, in which the entraining area of the jet has been increased by dividing it into a number of smaller streams by means of bridges. The increase of area is, however, in such nozzles, obtained at the expense of an increase of back pressure, it being obvious that any obstruction in the form of a rib, bridge, or wall, induces a baffling effect, which interferes with the free flow of steam and correspondingly increases back pressure.

The exhaust pipe of my invention presents no obstructions of any kind to the flow of the exhaust steam, the jet of steam, in passing through the pipe, merely changing its transverse section from that in which it enters the exhaust pipe, from the cylinder saddle, to one which will present the largest practicable area of entraining surface to the gases of combustion.

In the accompanying drawings: Figure 1 is a vertical transverse section through the smoke box and stack of a locomotive engine, illustrating an application of my invention; Fig. 2, a vertical central section, on an enlarged scale, through the exhaust pipe; Fig. 3, a similar section, taken at a right angle to Fig. 2; Fig. 4, a bottom plan view; Figs. 5, 6, and 7, horizontal sections, on the lines *a a*, *b b*, and *c c*, respectively, of Fig. 3; Fig. 8, a top plan view; Fig. 9, a bottom plan view of an exhaust pipe having four exhaust steam passages; Fig. 10, a horizontal section through the same, on a plane corresponding with the line *b b* of Fig. 3; and Fig. 11, a top plan view of the same.

Referring first to Figs. 1 to 8, inclusive, in the practice of my invention I provide an exhaust pipe, the body, 1, of which is integral and is provided with an external flange, 1^a, adjacent to its lower end, through which it is adapted to be secured to the cylinder saddles, X X, of a locomotive engine, above the exhaust passage, *x x*, thereof. The body of the exhaust pipe is divided, throughout substantially its entire length, by a vertical partition, 1^b, into two continuously independent exhaust steam passages, 2, 3, each of which conforms in transverse section, at its lower end, to the adjoining exhaust passage, *x*, of the cylinder saddle with which it communicates, which passage is, in this instance, shown as of rectangular transverse section, but may be of any other preferred section. The top of the exhaust pipe is devoid of external or internal projections, and, by a corresponding progressive variation of the transverse section of the separating partition, the transverse section of the two exhaust steam passages, 2, 3, is, as shown by the sectional views, Figs. 5, 6, and 7 gradually changed from that of their bases to that of two discharge orifices or nozzles 2^b, 3^b, located at the top of the exhaust pipe, each of which nozzles is in the form of nearly a half annulus, the two nozzles being separated one from the other, by the flat portion of the partition, 1^b. As said partition does not lie in the path of the currents of exhaust steam, it will be seen that it offers no obstruction to its free flow through the passages, 2, 3, to the nozzles 2^b, 3^b, and therefore that there is no increase of back pressure on the pistons.

The change of transverse section of the ex-

haust steam passages, from that of their lower openings to that of the half annulus nozzles by which they terminate at their upper ends, is effected by variation of the 5 transverse section of the separating partition, 1^b, which is widened at bottom in one direction, to completely separate the exhaust steam passages and cylinder saddle passages, as shown in Fig. 2, and has an outwardly 10 coned or tapered spreader, 1^c, extending from said widened portion to its upper end, said spreader forming the upper inner walls of the exhaust steam passages and nozzles.

As herein exemplified, each of the exhaust 15 steam passages, 2, 3, is twisted or helically curved, from one side of the longitudinal central plane of the exhaust pipe, at bottom, to the opposite side of said plane, at top, this being effected by correspondingly curving 20 the separating partition, 1^b. As a result of this curvature of the exhaust steam passage, the currents of exhaust steam which leave the cylinder passages, parallel with the longitudinal central plane of the smoke 25 box, are discharged thereinto, transversely to said plane, and to the direction of traverse of the gases passing out of the boiler tubes, in which direction the exhaust steam acts more effectively to convey them into the 30 stack. The flow of the exhaust steam may, however, be conducted on substantially vertical lines if preferred.

It will be seen that by the change of transverse section of the exhaust steam passages 35 from that of their receiving ends to that of their discharge nozzles, a material increase of entraining surface of the exhaust jets upon the gases of combustion is afforded, and that such increase is obtained without 40 involving increase of back pressure by the obstruction of bridges or projections. Further, the flow of the gases to the stack, which takes place on both the inner and the outer sides of the half annulus exhaust nozzles, is 45 unimpeded by any flanges or other exterior projections on the exhaust pipe.

In order to enable the area of the nozzles, and consequently the force of the exhaust blast, to be readily and conveniently varied 50 as may, from time to time, be found necessary or desirable, a conical cap, 4, may be connected detachably to the exhaust pipe by a bolt, 4^a, secured axially in the partition, 1^b, to which the cap is connected by a nut, 4^b. 55 By the attachment of a cap of greater or less diameter, which can be readily effected, the area of the exhaust nozzles, 2^a, 3^a, may be increased or diminished as desired.

For the purpose of easing the flow of the 60 gases of combustion to the exhaust nozzles, and eliminating the angle between the exhaust pipe and the table plate, y, of the locomotive smoke box, a conical ring, 5, may be fitted around the exhaust pipe, above the 65 table plate, and bolted to the latter, this con-

struction enabling an effective joint to be made between the exhaust pipe and table plate.

Figs. 9 to 11, inclusive, illustrate a structural modification, suitable for application 70 in connection with cylinder saddles in which separate passages are provided from the opposite ends of the cylinders to the exhaust pipe. For such applications, four exhaust steam passages, 2, 2^a, 3, 3^a, are formed in the 75 exhaust pipe, said passages terminating, at their upper ends, in exhaust nozzles, 2^b, 2^c, 3^b, 3^c, each of which is a segment of an annulus (approximately one fourth) and being 80 changed in transverse section, from their receiving to their discharge ends, as in the construction first described. While the use of separate passages from the opposite ends of the cylinders to the exhaust pipe is not 85 common practice in locomotive construction, it is considered by me to be of advantage, as the separation of the currents of exhaust steam from the opposite ends of the cylinders, throughout their entire traverse to the 90 exhaust nozzles, will materially reduce the back pressure which is exerted in the operation of ordinary exhaust mechanisms. This 95 reduction of back pressure is due to the fact that the traverse of the current of steam from each end of the cylinder to the discharge nozzle is effected without obstruction from, or interference by, that of the current from the opposite end, and without involving variation in the transverse sectional area 100 of the passage from the cylinder to the discharge nozzle, the effect of which variation is to interrupt the uniform and unbroken flow of the current of exhaust steam, with the result of causing an increase of back pressure.

I claim as my invention and desire to secure by Letters Patent:

1. In a locomotive exhaust pipe, the combination of an integral tubular body or casting, the top of which is of cylindrical section and devoid of external projections; longitudinal partitions, dividing said body into four continuously independent exhaust steam passages, each adapted to register at bottom with the exhaust passage of one end only 110 of a locomotive cylinder, and an integral outwardly coned central spreader, the spaces between the top of which, the sides of the partitions, and the outer walls of the exhaust steam passages form independent exhaust 115 nozzles for the ends of two locomotive cylinders.

2. In a locomotive exhaust pipe, the combination of an integral tubular body or casting, the top of which is of cylindrical section and devoid of projections; longitudinal partitions dividing said body into continuously independent exhaust steam passages, from bottom to top; and an integral 125 outwardly coned central spreader, the spaces 130

- between the outer walls of said exhaust steam passages and the partition and spreader being progressively varied in cross section from that of the locomotive cylinder
- 5 6 exhaust passages, at bottom, to segmental annular exhaust nozzles, at top.
3. In a locomotive exhaust pipe, the combination of a tubular body or casing; a helically curved longitudinal partition, di-
10 viding said body into continuously independent exhaust steam passages, each adapted to register at bottom with a locomotive cylinder exhaust passage, and an integral outwardly coned central spreader, the spaces
15 between the top of which, the sides of the partition, and the outer walls of the exhaust steam passages form independent exhaust nozzles.
4. In a locomotive exhaust pipe, the combination of a tubular body or casing, helically curved longitudinal partitions, dividing said body into four continuously independent exhaust steam passages, each adapted to register, at bottom, with the exhaust
25 passage of one end only of a locomotive cylinder, and an integral outwardly curved central spreader, the spaces between the top of which, the sides of the partitions, and the outer walls of the exhaust steam passages
30 form independent exhaust nozzles for the ends of two locomotive cylinders.
5. In a locomotive exhaust pipe, the combination of a tubular body or casing; a helically curved longitudinal partition, divid-
35 ing said body into independent exhaust steam passages, each adapted to register at bottom with a locomotive cylinder exhaust
- passage; an integral outwardly coned central spreader, the spaces between the top of which, the sides of the partition, and the outer walls of the exhaust steam passages form independent exhaust nozzles; an inwardly and upwardly tapered cap, of circular section, fitting around the top of the spreader; and a central bolt, connecting said cap detachably to the spreader. 40
6. In a locomotive exhaust appliance, the combination of an exhaust pipe of substantially cylindrical form at its upper portion; a horizontal smoke box table or separating plate through which said exhaust pipe extends; and a ring fitting on said plate and around the exhaust pipe, and having its outer surface continuously upwardly and inwardly curved. 45
7. In a locomotive exhaust pipe, the combination of a tubular body or casing, the top of which is of cylindrical section, and is devoid of projections; a longitudinal partition, dividing said body into independent exhaust steam passages, each extending from the bottom of the body of the pipe, at which it is adapted to register with a locomotive cylinder exhaust passage, to the top of said body; and an integral outwardly coned central spreader, the spaces included between the top of which, the wall of the body, and the sides of the longitudinal partition, form independent exhaust nozzles, each of segmental annular section. 50
